UNITED STATES PATENT OFFICE.

TRUMAN J. GLOVER, OF MILLBURN, NEW JERSEY, ASSIGNOR TO FEDERATED ENGINEERS DEVELOPMENT CORPORATION, OF JERSEY CITY, NEW JERSEY, A CORPORATION OF DELAWARE.

LABEL-HANDLING MECHANISM.

Application filed February 9, 1924. Serial No. 691,691.

To all whom it may concern:

Be it known that I, TRUMAN J. GLOVER, a citizen of the United States, and a resident of Millburn, in the county of Essex and State of New Jersey, have invented a new and Improved Label-Handling Mechanism, of which the following is a full, clear, and exact description.

This invention relates to improvements in mechanism for handling stacked sheets of flexible material, particularly to an apparatus for transferring one sheet at a time from the top of a stack to a convenient position adjacent the stack.

An object of the invention is to provide a mechanism of this character particularly adapted for co-action with an automatic record press and so designed that labels may be expeditiously and accurately handled.

The invention contemplates the provision of means for picking up a label from a stack, transferring it to an adjacent table, and dropping it, and further objects of the invention are to provide simple, practical and efficient mechanism for carrying out this series of operations.

In the operation of presses for molding disc phonograph records, it is customary to manually remove the two top-most labels from a stack and lay them on the co-acting die surfaces of the press before the plastic record forming material is inserted between the dies. The finished record includes a label on each face. Inasmuch as the presses are operated at great speed and the gummed labels are very difficult to separate, considerable difficulty involving a loss of time in the operation of the presses has been encountered in manually picking up the labels and laying them on the dies. It is primarily to overcome this difficulty that the present mechanism has been devised. It will, of course, be understood that the invention may have other and broader applications.

In the accompanying drawings,

Fig. 1 is a view principally in elevation of my improved label handling mechanism, parts being broken away and in section for clearness.

Figs. 2 and 3 are similar views, showing successive positions of the mechanism as it is operated to remove the top-most label from a stack and deliver the same on an adjacent table, and

Fig. 4 is a transverse sectional view on 55 the staggered line 4—4 of Fig. 1.

Referring with particularity to the drawings, it will be noted that I have used the reference character 10 to designate general supporting frame work for my improved mechanism. This frame work may consist, as shown, of a pair of parallel horizontal bars 11 between which are arranged transverse connecting bars 12. A table 13 upon which labels are to be delivered, is hung from the frame work in any convenient manner and an open-topped receptacle 14 within which the labels 15 to be transferred are stacked, is supported upon a bracket 16 secured to the table.

Extending between the frame bars 12 are a pair of parallel rods 17, upon which sleeves 18 are slideable. The forward ends of these rods are disposed above the table 13. The ends of the sleeves 18 which are furthest removed from the table carry hangers 19, and a rock shaft 20 is borne by the hangers. Near their opposite ends, the sleeves 18 support a cross bar 21, upon which the intermediate portion of a lever 22 is fulcrumed. A spring 23 anchored to the rear frame bar 12 and connected to the cross bar 21, serves to normally retain the sleeves 18 and the mechanism which they carry in the position shown in Fig. 1, with the ends of the sleeves 45 abutting against stop nuts 24 at the rear ends of the guide rails 17.

As seen most clearly in Fig. 4, brackets 25 turnable upon the rock shaft 20 carry hollow arms 26, to the forward ends of which are 90 attached suction cups 27.

I have indicated a plurality of arms 26 and cups 27 for simultaneously transferring the uppermost labels from a plurality of different stacks. All of these arms are controlled by the same mechanism and operate in exactly the same manner, and a detailed description of the operation of one may suffice for the operation of all.

Each arm 26 is connected at its rear end 100 to a flexible tube 28, which is in turn connected to an air pump 29. The same pump may be used in simultaneously controlling all of the suction cups. It will be noted that the pump 29 includes a piston 30 working in the pump cylinder, the rod 31 of the piston being operatively connected to a crank shaft 32. On the up stroke of the piston, suction

will be produced in all of the cups 27 and on the down stroke of the piston, air will be forced through the cups.

Referring now to the mechanism for controlling the mechanical movements of the arms 28, it will be seen that the lower end of the lever 22 has a slot and pin connection with a latch bar 35 fixed intermediate its ends to the rock shaft 20. The opposite end 10 of the latch bar is formed with a latch 36 normally retained by a keeper 37 (Fig. 1). Rocking movement of the lever will effect elevation of the forward end of the latch bar, and consequent release of the latch to 15 permit forward movement of the sleeves 18 along the guide rails. Lever 22 is formed with an upwardly extending substantially U-shaped portion 40, one extremity of which carries a yieldingly mounted buffer pin 41 20 disposed in the path of a travelling actuator bar 42.

The weight of the arms 26 ordinarily causes the suction cups to rest upon the stacks of labels 15 in the receptacle 14, but 25 means is provided for elevating the cups and moving them over the tables 13. This means consists of lifting cams 43 fixed upon the shaft 20, and carrying laterally projecting pins 44 which engage under the arms 26 30 to effect elevation thereof.

The pump 29 is of course operated in timed relationship with an actuator bar 42 and the manner of operation of the mechanism may be briefly described as follows. 35 Actuator bar 42 travelling from the position shown in Fig. 1 to the position shown in Fig. 2 engages the yielding buffer 41, rocking the lever 35 on its fulcrum until it engages the stop 50 and consequently releases 40 the latch 36. The movement of the latch bar 35 effects turning of the rock shaft 20, and consequently moves the pins 44 of the lifting cams into engagement with the arms 26, turning the brackets 25 on the rock shaft, and elevating the suction cups. 45

As seen in Fig. 2, the piston 30 of the pump 29 is on its up stroke when the actuator bar engages the buffer so that as the suction cups are lifted, they carry with them 50 the uppermost label from each stack. Continued movement of the actuator bar moves the mechanism controlled by the lever 40 to the position shown in Fig. 3, the sleeves 18 sliding forwardly on the bars, carrying with 55 them the hangers 19 and the shaft 20 which they support, and moving the suction cups over the table 13.

When the actuator bar reaches this position, the piston 30 of the pump is moving 60 toward the bottom of the cylinder, forcing air through the tubes 28 in the hollow arms 26, and consequently effecting release of the labels from the suction cups, causing the labels to drop upon the table. As the bar 65 42 returns from the position of Fig. 3 to

that shown in Fig. 1, the spring 23 will return the sleeves 18 to their normal position, the combined weight of lever 22, arms 26 and latch bar 35 co-operating to restore the latch bar to the position shown in Fig. 1, 70 and permitting the suction cups to again rest on the topmost labels of the various stacks. The means for synchronizing the operation of the pump and the actuator bar forms no part of the present invention, and 75 obviously, any means might be utilized for this purpose.

Numerous slight changes and alterations might be made in the general form and arrangement of the parts described without 80 departing from the invention, and hence I do not wish to limit myself to the precise details set forth but shall consider myself at liberty to make such changes and alterations as fairly fall within the spirit and 85 scope of the appended claims.

I claim:

1. In a pneumatic sheet handling mechanism, a travelling carriage, a pneumatic pick-up device carried thereby, driving means for moving said carriage, and means on the carriage controlled by said driving means for lifting the pick-up device prior to the movement of the carriage. 90

2. In a pneumatic sheet handling mechanism, a reciprocable carriage, a pneumatic pick-up device pivoted thereon, a lever on the carriage operable to lift said pick-up device, and means for moving the carriage in one direction, said means being associated 100 with the lever to raise the pick-up device before moving the carriage.

3. In a pneumatic sheet handling mechanism, a reciprocable carriage, a pneumatic pick-up device pivoted thereon, means operable to lift such pick-up device, and actuating means for advancing the carriage through the intermediacy of the aforementioned means whereby the pick-up device 105 will be lifted prior to the advancement of the carriage.

4. In a pneumatic sheet handling mechanism, a reciprocable carriage, a pneumatic pick-up device pivoted thereon, means operable to lift said pick-up device, actuating means for moving the carriage in one direction through the intermediacy of the aforementioned means whereby the pick-up device will be lifted prior to movement of the carriage, and a spring adapted to return the carriage to initial position. 115

5. In a pneumatic sheet handling mechanism, a reciprocable carriage, a pick-up device carried thereby, actuating means for advancing the carriage, a spring for returning the carriage to initial position, a latch for holding the carriage in initial position, and means controlled by said actuating means for raising the pick-up device and 120 releasing the latch. 130

6. In a pneumatic sheet handling mechanism, a frame, a reciprocable carriage mounted to slide thereon, a pick-up device carried by the carriage, a keeper on the frame, a latch lever on the carriage adapted normally to engage the keeper, means on said latch lever for raising the pick-up device, an actuating lever on the carriage associated with the latch lever, actuating means adapted to engage the actuating lever and operating initially to raise the pick-up device and release the latch and then to move the carriage forward.

7. In a pneumatic sheet handling mechanism, a frame, a reciprocable carriage adapted to slide thereon, a pick-up device pivoted upon the carriage, a keeper on the frame, a latch lever on the carriage normally engaging the keeper, means on said latch lever for raising the pick-up device, an actuating lever on the carriage associated with the latch lever, a reciprocating driver adapted on the forward stroke thereof to engage the actuating lever initially raising the pick-up device and releasing the latch and then moving the carriage forward, and a spring adapted to restore the carriage on the return stroke of the driver and permitting the latch lever to engage the keeper and the pick-up device to drop by gravity.

8. In a pneumatic sheet handling mechanism, a reciprocating carriage, a pick-up device pivoted thereon, a reciprocating driver for advancing the carriage, a latch for holding the carriage in normal position, a lever system for releasing the latch and raising the pick-up device, a spring buffer on the lever system adapted to be engaged by the actuating driver whereby the pick-up device is raised and the latch is released before the carriage moves forward, and a spring for returning the carriage to initial position on return of the actuating driver.

9. In a pneumatic sheet handling mechanism, a frame, a reciprocable carriage mounted to slide thereon, a pick-up device pivoted to the carriage and adapted to rest

on the material to be picked up, a keeper on the frame, a latch lever on the carriage adapted normally to engage the keeper, means on said latch lever for raising the pick-up device, an actuating lever on the carriage associated with the latch lever, actuating means adapted to engage the actuating lever and operating successively to raise the pick-up device, release the latch and advance the carriage and pick-up device, and means for controlling suction and pressure in said pick-up device, operable in timed relation with movement of the pick-up device.

10. In a pneumatic sheet handling mechanism, a receptacle for the sheets to be picked up, a reciprocable carriage, a pick-up device pivoted upon the carriage and resting upon said sheets, a latch adapted to hold the carriage in initial position, means associated with the latch for raising the pick-up device, an actuating lever on the carriage associated with the latch, a reciprocating driver adapted to engage the actuating lever, said driver operating on one stroke successively to raise the pick-up device clear of the receptacle, release the latch and advance the carriage, and an air pump for alternately producing suction and pressure in the pick-up device and timed to produce suction in the pick-up device during the raising of the pick-up device and the forward movement of the carriage.

11. A pneumatic sheet handling mechanism, a pneumatic pick-up device, an arm upon which said device is supported, a traveling carriage upon which said arm is pivotally mounted, means for normally locking the carriage against reciprocation, actuating means engageable with the carriage to effect movement thereof in one direction, means controlled by said actuating means for releasing the locking means, and lifting the arm prior to the movement of said carriage.

TRUMAN J. GLOVER.
